H. Holt,
Hand, Stampk.

No. 10731.

Patented Mar 3 1857

UNITED STATES PATENT OFFICE.

HORACE HOLT, OF WINCHESTER, MASSACHUSETTS.

HAND-STAMP.

Specification of Letters Patent No. 16,781, dated March 3, 1857.

To all whom it may concern:

Be it known that I, HORACE HOLT, of Winchester, in the county of Middlesex and State of Massachusetts, have invented certain new and useful Improvements in Hand-Stamps, of which the following is a full, clear, and exact description, reference being had to the accompanying drawings, making part of this specification, in which—

10 C, is the pedestal or base from which rises the standard D supporting the moving parts of the apparatus; to the upper part of this standard are attached the lugs E between which plays the handle F pivoted at *a* and 15 having the arm G and toe *b* (seen dotted in the drawing). To one side of the standard is attached the sleeve H in which plays the rod I to the bottom of which is attached the die or stamp K; this rod is held up in 20 the position shown in the drawing by a spiral spring L the end of the arm G resting on the top of the rod I. The inking roll M is hung in the arms N which are pivoted at *c* one on each side of the sleeve H; the 25 axle of the roll plays up and down in slits *d* in the lower end of the arm N being held up to its work by the springs *f* there being one at each end of the roll. To each of the arms N are pivoted at *g*, near the upper end, 30 the short arms P which are connected together by the cross piece L from which projects between the lugs E the dog *i* against the end of which rests the toe *b*, the spring *m* which is attached at *n* to each 35 side of the standard D and which presses against the cross piece L serving to keep the ink roll up in the position shown in the drawing when not forced therefrom by the movement of the handle F.

R is the platen on which the article to be stamped is placed; it is covered with cloth in the ordinary manner.

Operation: The handle F being moved in the direction of the arrow until its end reaches A the toe *b* pressing against the dog *i* forces the roll M in the direction of the arrow A' beneath the die K inking the face of it, the springs *f* causing the roll to accommodate itself to the surface of the die. The handle F is now moved in the opposite direction toward B the point of the arm G pressing upon the rod I forces the die K down vertically upon the platen R or upon the article to be stamped as shown dotted at B'. In moving the handle from A toward B as it regains its vertical position the spring *m* throws the roll M back into its original position before the rod I commences its vertical descent. When the impression has been made and the hand of the operator is removed from the handle the spring L raises the rod I into its original position the top of the die K resting against the bottom of the sleeve H.

I do not claim operating the platen or stem and the inking roll by a single operation of the hand but

What I do claim as my invention and desire to secure by Letters Patent is—

The combination of a detached lever with its toe pieces for inking and taking the impression, when said inking and impressing devices are returned to their places by springs as set forth.

HORACE HOLT.
